(57) **CLAIM**

I claim the ornamental design for a tapered integral handle pre-form, as shown and described.

DESCRIPTION

FIG. 1 is a front elevational view of my new design for a tapered integral handle pre-form;

FIG. 2 is a perspective view thereof;

FIG. 3 is a rear elevational view thereof;

FIG. 4 is a left side elevational view thereof;

FIG. 5 is a right side elevational view thereof;

FIG. 6 is a top plan view thereof; and,

FIG. 7 is a bottom plan view thereof.

The broken lines shown in the drawings represent unclaimed portions of the design.

1 Claim, 6 Drawing Sheets# US D962,769 S
